DESIGN FOR A SIGNAL LIGHT

Arthur T. Newell, Huntington, N. Y., assignor to
Kenyon Instrument Co., Inc., Huntington Sta-
tion, N. Y., a corporation of New York

Application November 23, 1945, Serial No. 123,973

Term of patent 14 years

(Cl. D72—1)

To all whom it may concern:

Be it known that I, Arthur T. Newell, a citizen of the United States, residing at Huntington, in the county of Suffolk and State of New York, have invented a new, original, and ornamental Design for a Signal Light, of which the following is a specification, reference being had to the accompanying drawing, forming part thereof.

Fig. 1 is a side elevation of the signal light showing my new design;

Fig. 2 is a front elevation thereof;

Fig. 3 is a top plan view thereof; and

Fig. 4 is a rear elevation thereof.

I claim:

The ornamental design for a signal light, sub-
stantially as shown.

A. T. NEWELL.
